CLAIM

I claim the ornamental design for the spherically-shaped lip balm, as shown and described.

DESCRIPTION

FIG. 1 is a top perspective view of a spherically-shaped lip balm showing my new design;

FIG. 2 is a top plan view thereof;

FIG. 3 is a front elevation view thereof;

FIG. 4 is a rear elevation view thereof; and,

FIG. 5 is a side elevation view thereof.

The broken line portion of the figure drawings is included to show unclaimed subject matter only and forms no part of the claimed design.
